UNITED STATES PATENT OFFICE.

JOHN A. JOHNSON, OF CRAWFORDSVILLE, AND THEODORE N. JOHNSON, OF WAVELAND, INDIANA, ASSIGNEES, BY DIRECT AND MESNE ASSIGNMENTS, TO JOHNSON ACETYLENE GAS COMPANY, OF CRAWFORDSVILLE, INDIANA, A CORPORATION.

ACETYLENE-GAS GENERATOR.

1,179,837.

Specification of Letters Patent.

Patented Apr. 18, 1916.

Application filed September 12, 1914. Serial No. 861,399.

To all whom it may concern:

Be it known that we, JOHN A. JOHNSON and THEODORE N. JOHNSON, citizens of the United States, residing at Crawfordsville and Waveland, respectively, in the county of Montgomery and State of Indiana, have invented certain new and useful Improvements in Acetylene-Gas Generators, of which the following is a specification.

- 10 This invention relates to that class of acetylene gas generators wherein the rise and fall of the water-sealed hood inclosing the carbid holding receptacle actuates the valve which controls the flow of carbid into the generating chamber, the construction herein shown and described being different from that shown and described in our former Letters Patent of the United States No. 1,130,906 issued March 9, 1915.
- 15 The hereinabove mentioned generators, in some instances, are constructed so that the hood and gas-bell are joined and moved together, so that considerable gas is necessary to provide the buoyancy for overcom-
- 20 ing the combined weight of the hood and bell, so that the action of the valve is delayed, thereby allowing an excessive amount of carbid to flow into the generating chamber and producing an excessive amount of
- 25 gas over and above the capacity of the machine. This is both expensive and dangerous, expensive because the excessive amount of gas finds its way to the outside and is lost, and dangerous because leakage
- 30 of gas is liable at any time to bring disaster.

The object of this invention is to provide means whereby the buoyancy of the initially generated gas will initially cause the hood to rise a short distance independently of the gas-bell, so that the said valve is closed and further flow of carbid discontinued at a time when a quantity of carbid will have been discharged to provide a volume of gas within the capacity of the machine.

We accomplish the above object of the invention by means of the construction illustrated in the accompanying drawings, forming a part hereof, in which—

35 Figure 1 is a central vertical section through a complete acetylene gas generator, showing our invention in operative position. Fig. 2 is a fragmentary detail view in side elevation of the hood and gas-bell,

showing our improved connection between 55 said hood and bell, on the dotted line 2—2 in Fig. 1.

Referring to the drawings, the generator contemplates the use of the usual casing 10, which is divided centrally by a transverse 60 division wall 11 which terminates in a vertically disposed neck 12. The upper end of the neck 12 supports the usual carbid holding receptacle 15. The water above the division wall 11 forms a water-seal for the 65 lower end of the usual gas-bell 20 and the hood 22 which incloses the carbid-receptacle 15 and prevents leakage of gas around said receptacle. When the gas is initially generated in the generating-chamber 25 the 70 gas immediately rises and passes up through the neck 12 and apertures 13 and accumulates within the hood 22, for the reason that sufficient gas within the generating-chamber must be generated to break the 75 water-seal in the stand-pipe 27 before the gas can gain access to the interior of the gas-bell 20. In that class of generators in which the bell and hood move in unison there is a combined weight which must be 80 overcome before the hood is moved out of contact with the mechanism which actuates the valve in the discharge opening of the carbid holding receptacle, so that by the time the valve is released an excessive 85 amount of carbid has been discharged into the generating-chamber to produce an amount of gas in excess of the capacity of the machine. This feature is sought to be remedied by those working in this art for 90 the reason that the waste of gas means a higher cost of operation, and through this waste, through leakage, there is always danger of accidents caused through premature explosions.

95 It will be noted in examining our construction, that the gas initially generated immediately begins to act upon the hood 22 for the reason that initially the latter is free of interference in its movements, so 100 that only a small amount of gas is necessary to elevate it and move it out of contact with the mechanism that controls the movement of the valve in the discharge end of the carbid holding receptacle. At this time, 105 when the valve closes the discharge opening in the carbid holding receptacle, sufficient carbid will have been discharged into the generat-

ing-chamber to produce sufficient gas the buoyancy of which, and having the hood under movement, is sufficient at this time to elevate both the hood and bell, and further, the carbide so discharged into the generating-chamber will produce only an amount of gas that can readily be taken care of within the gas-bell 20. This diversity in movemnt between the hood 22 and the gas-bell 20 is se-
cured by means of a pair of uprights 30 which are secured to the bell on opposite sides of the hood. As shown, the uprights 30 extend upwardly and parallel with the outer surface of the hood 22, and near the upper ends of the uprights 30 elongated slots 32 are provided which engage with a pair of horizontally projecting lugs 33 formed integrally with the top 35 of the hood 22. By means of this construction it will be observed that the gas intially generated will elevate the hood 22 a sufficient distance to release the valve controlling the discharge opening in the carbide holding receptacle before the lugs 33 engage the upper edges of the elongated slots 32, after which the hood 22 and gas-bell 20 are moved upwardly at the same time. This is quite an advantage, as has heretofore been set forth, for the reason that the hood 22 is more easily affected through the buoyancy of the gas than the bell 20, and as the valve in the discharge end of the carbide holding receptacle is actuated by the former the accuracy of its action is more readily determined and maintained.

The gas in passing out of the bell 20 enters the top of the pipe 40 and after passing downward through said pipe enters the service pipe 41. The pipe 40 is considerably enlarged to afford room for a suitable

porous material for extracting and collecting moisture from the gas as it passes toward the service pipe, and as the water condenses within the pipe 40 it drains to the bottom and passes out through the drain pipe 42 and is discharged exteriorly of the casing 10.

Having thus fully described our said invention, what we desire to secure by Letters Patent, is—

1. In an acetylene gas generator, the combination, of a gas generating chamber, a carbide holding receptacle arranged with its discharge end toward said chamber, a water sealed gas bell, a water sealed means arranged within said gas bell and communicating with said generating chamber, a water sealed hood inclosing said carbide holding receptacle, and connecting means between said hood and gas bell allowing said hood to be raised initially a prescribed distance independently of said gas bell.

2. In an acetylene gas generator, the combination, of a generating chamber, a carbide holding receptacle, a gas bell for storing gas, a pair of uprights secured to and moving with said bell and extending upwardly along the opposite sides of said hood, and means carried by said hood and forming connections with said uprights for permitting said hood to intially move a prescribed distance independently of said bell.

In witness whereof, we have hereunto set our hands and seals at Crawfordsville, Indiana, this 7th day of September, A. D. one thousand nine hundred and fourteen.

JOHN A. JOHNSON. [L.S.]
THEODORE N. JOHNSON. [L.S.]
